UNITED STATES PATENT OFFICE.

PATENT AWARDED HENRY A. HALLUM, OF SEATTLE, WASHINGTON.

ELECTROLYTIC CELL.

1,818,993.

Specification of Letters Patent. Patented Oct. 14, 1919.

Application filed July 30, 1918. Serial No. 247,460.

To all whom it may concern:

Be it known that I, HENRY A. HALLUM, a citizen of the United States, residing at Seattle, in the county of King and State of Washington, have invented certain new and useful improvements in Electrolytic Cells; and do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in electrolytic cells, and consists of a simple and efficient device of this nature having various details of construction, combinations and arrangements of 20 parts which will be hereinafter fully described, shown in the accompanying drawings and then specifically defined in the appended claim.

25 My invention is illustrated in the accompanying drawings which, with the numerals of reference marked thereon, form a part of this application and in which:

30 Figure 1 is a perspective view of one of the cells, showing poles in dotted and full lines therein.

Fig. 2 is a vertical central sectional view through a cell, parts being shown in elevation.

35 Fig. 3 is a detailed perspective of parts disassembled.

Fig. 4 is a detailed view in perspective, showing the electrode, or positive pole, with ribs thereon.

40 Fig. 5 is a detailed view through a portion of a cell, asbestos sack, and means for holding the latter from engagement with the cell.

Fig. 6 is a view showing the water mechanism for supplying the cell, and

45 Fig. 7 is an enlarged detail view through the positive pole and buss bar terminal.

Reference now being had to the details of the drawings by numerals:

50 1 designates a cell which acts as a negative pole, as well as a container for the electrolyte or caustic soda solution and has two poles therein upon each side of the cell and spaced apart a slight distance from the wall of the cell in order to permit the electrolyte 55 to freely circulate about the same. The ad-

ditional poles on each side of the cell will also act as stabilizers for the electrolyte, preventing any surging which would be caused by the current passing through the cells. The negative pole will provide a large area 60 for the hydrogen to be given off, as well as acting as stabilizers for the electrolyte and preventing a surging, which will be caused by the current passing through the same and which causes the electrolyte, together with 65 the hydrogen which is being given off from the negative pole, to be thrown against the asbestos curtain or diaphragm 3, shown in Figs. 2 and 3 of the drawings, and which is fastened to the bell 4 by means of a peripheral bar 5.

Said cell is provided with an intake pipe 7 for refilling the cell with water, and 8 is a pet-cock which affords means for ascertaining the proper height of the electrolyte within the cell. At point designated by numeral 9, one end of the buss bar is adapted to be soldered, and numerals 10 and 11 designate hard rubber insulators placed one near each lower end of the cell, and serves to prevent 80 the electrode or positive poles from short circuiting with the cell or negative pole. A hydrogen outlet is designated by numeral 13, and 14 designates an outlet for oxygen which outlets are provided with suitable 85 hard rubber insulators 15 and 16 which will prevent the bell 4 from coming in contact with the negative pole which, if a contact were made, would have a tendency to permit the hydrogen to enter the oxygen bell 4. 90 Numerals 17 designates the terminal of the positive pole, upon which are suitable insulators 18 and having preferably a hole therein of sufficient depth in its top to permit soldering in of one end of the buss bar. 95 Said insulators 18 insulate the electrode, or positive pole from the oxygen bell 4, as well as insulating the positive pole from the cell proper, and by this manner of insulation the bell becomes a neutral member, making 100 it possible to produce oxygen of a purity of a very high percentage. Hard rubber insulators 20 are placed on the electrode to prevent the same from coming in contact with the oxygen bell 4. 105

Referring to Fig. 4 of the drawings will be seen a detailed view of a portion of the electrode or positive pole, provided with a number of ribs 21 welded in position and spaced apart, to provide ample surface for 110

the electric current to pass through the same, as well as to provide ample surface for the electrolyte to come in contact with the electrode, or positive pole, for the purpose of carrying off the electric current as it passes from the positive to the negative pole. Said ribs overcome the necessity of having to provide a large cell, as the number of square inches in the electrode will be equal to the 10 largest electrode which might have a square surface large enough to permit an amperage of 500 to pass through without overworking or overheating the cell, and which sets up a resistance of only 2.3 volts at 500 amperes, 15 producing three and one-half cubic feet of oxygen and seven cubic feet of hydrogen per hour.

In Fig. 5 of the drawings ribs 22 are shown placed at such angles as to prevent 20 the asbestos diaphragm 3 from rubbing against the ribs of the electrode proper, as well as permitting all oxygen given off from the same to pass upward through the channels of the electrode into the oxygen bell. Said channels have the tendency of guiding 25 all the oxygen upward into the oxygen bell, and will prevent the oxygen from being thrown against the asbestos diaphragm, as in the event of there being a faulty weave or 30 hole in the latter, oxygen would then pass up and mix with the hydrogen gas.

In Fig. 3 of the drawings a cell is broken away to illustrate the position of the oxygen bell and the relative position of the oxygen bell and top cover, and means for fastening 35 the asbestos diaphragm to the bell and which diaphragm acts as a partition between the negative and positive poles, allowing, however, the electrolyte, as well as the electric 40 current, to pass through the asbestos unhindered but preventing the oxygen and hydrogen gases from mixing. Said cover or top 25, when adjusted in place, is welded to prevent the escape of hydrogen.

In Fig. 7 of the drawings is illustrated 45 an enlarged view of the positive pole terminal 17 with the insulators 18, insulating the oxygen bell, as well as the top cover, which becomes a part of the negative pole 50 when welded to the cell.

Referring to Fig. 6 of the drawings will be seen the apparatus for automatically feeding water to the cell, and in which a water supply pipe 26 is provided with a dome 27, 55 and 28 and 29 are pipes leading through the wall of the pipe 26 and the upper end of said pipe 28 opening into said dome and which passes through a plug 30 in the intake pipe 7, while a second pipe 29 leads from the pipe

26 to the pipe 7 and opens below the lower end of the pipe 28. By this construction of apparatus, small quantities of water may be replaced from time to time in the cell and which will prevent the latter from cooling, which would retard the production of the 60 gases, and which is one of the common faults of many of the cells now in use, as they are filled only two or three times during twenty-four hours and which necessarily takes a large amount of cold water to bring the electrolyte to its proper level in the cell. Said pipe 26 extends preferably the length of the cells and is provided with an outlet directly above the intake pipe upon each cell, and the pipe is connected to a reservoir at one 70 end of the cells, which may be provided with a float so arranged that the level of the water in the pipe line may be maintained in the dome. The pipe 28, which terminates at its upper end near the top of the dome, extends 80 down through the intake pipe as far as the water level is to be maintained in the cell and the upper end of the pipe 29 is substantially flush with the water line of the pipe 26 and extends down into the intake pipe a sufficient distance to assure a beginning of a flow of water in the pipe 28, before the water is below the pipe 29, the theory being that as the water is lowered in the cell until the end of the pipe 28 is exposed, the confined air in 90 the dome will rush down and admit the flow of water into the pipe 29, until the water again rises and seals the pipe 28.

What I claim to be new is:

An electrolytic cell acting as a negative 95 pole or electrode and container for electrolyte, provided with a peripheral flange about its upper end, an apertured plate fastened to said flange, a positive electrode having a threaded stem passing through and insulated from said plate, an oxygen bell mounted upon said stem spaced apart from the positive electrode and said plate and insulated therefrom, said bell having an oxygen outlet passing through an aperture in the 100 plate and insulated therefrom, a diaphragm secured to the marginal edge of said bell and extending about the positive electrode, and means for holding the lower portion of the diaphragm spaced apart from the positive electrode.

In testimony whereof I hereunto affix my signature in presence of two witnesses.

HENRY A. HALLUM.
